ASH TRAY

James D. Gerahy, New York, N. Y., assignor to
 Aquatray, Incorporated, New York, N. Y., a corporation of New York

Application December 5, 1942, Serial No. 467,949

5 Claims. (Cl. 131—236)

This invention relates to that type of ash tray which utilizes a trough, well or other receptacle associated therewith or forming a part thereof and adapted to contain an extinguishing fluid, such as ordinary water, whereby the lighted end of a cigarette or cigar may be efficaciously and expeditiously extinguished by simply dipping it in the fluid before the cigarette or cigar is discarded. This is effective in preventing any possible conflagration, which might well prove to be both serious and expensive, occasioned by the discarding, either by design or by inadvertence, of lighted or partially lighted cigarettes or cigars and also it eliminates any possibility of disagreeable odors emanating from them before they have been completely extinguished.

The principal object of the invention is the production of an ash tray of the character indicated above in which the well or receptacle holding the extinguishing fluid is positioned centrally of the ash tray whereby ready access may be had thereto from any side of the ash tray.

A further object of the invention is the production of an ash tray of the general character referred to above in which the centrally disposed well or receptacle is removably and rigidly held in position by any suitable means provided in the base of the ash tray whereby the well or receptacle may be easily removed for filling or other purposes independently of the ash tray proper.

Still a further object of the invention lies in the combining with an ash tray of the general character described of a holder for cigars or cigarettes which may be removable and which shall be adapted to be supported by the extinguishing fluid well or receptacle and which shall constitute, in addition, a shield or screen, preferably plate-like in character, and so dimensioned and positioned as to permit discarded cigarettes, cigars, burnt matches or other refuse to be dropped into the ash tray without removal of the shield or screen while permitting it to act in hiding from view the unsightly and discarded contents of the ash tray.

To the above and other ends the present invention consists in the novel ash tray hereinafter described in detail and then specified in the claims.

Referring to the accompanying drawing illustrating a practical embodiment of the invention.

Fig. 1 is a plan view of an ash tray embodying the invention.

Fig. 2 is a horizontal section on the line 2—2 of Fig. 1.

Fig. 3 is a horizontal section on the line 3—3 of Fig. 2, and

Fig. 4 is a view similar to Fig. 2 but showing a modification and also omitting the cigarette-holding plate constituting a screen or shield.

The ash tray and parts thereof may be formed of any suitable material such as metal, metal alloys, glass, plastics, porcelain, synthetic materials, or even wood but it is preferable, for obvious reasons, that the material be of a non-inflammable character. The base of said ash tray is indicated at 10 and it is preferably, although not necessarily, rectangular in configuration. The side walls, which may be somewhat inclined, as illustrated, extend upwardly and outwardly from said base 10 and are indicated at 11. Said side walls are preferably integral with said base and with each other. The base 10 is provided with a bead or ridge 12 positioned centrally thereof and rectangular in configuration which is adapted to receive and frictionally hold and support the lower end of an extinguishing fluid trough or well 13 holding extinguishing fluid, such as water, and as is indicated at 14. The upper end of said well or receptacle 13 is open and the free edges of its walls are provided with inwardly extending beads forming a continuous bead 15. As the well or receptacle is firmly held to the base by friction only it may be readily and easily detached from said base for cleaning and filling purposes.

16 indicates a cigarette-holding plate which also constitutes a screen or shield provided with a plurality of suitably formed grooves 17 therein for receiving and supporting cigarettes or cigars and the like. A downwardly depending rectangularly-shaped four-walled flange 17' is provided which preferably is integral with the screen or shield and is of a size adapting it to extend downwardly within the well and to frictionally engage the bead 15 on the upper end of the well or receptacle. Said four-walled flange 17' provides or forms the walls of an opening 18 which extends through the screen or shield and is of a size adapting it to receive the lighted end of a cigarette, or in some cases, of a cigar. The side edges of the screen or shield 16 preferably terminate adjacent the upper ends of the walls 11 but the material which ordinarily would constitute the corners thereof has been removed or cut away to form inclinations 19 providing spaces between said inclinations and the corners formed by the meeting edges of adjacent walls 11 whereby discarded cigarettes, cigars, burnt matches or other refuse may be dropped or thrown within such spaces whereupon they will fall or slide down the inclined sides 11 and will come to rest on the base of said ash tray and into such position as to be

substantially hidden from view by the screen or shield 16.

It will be noted that the flange 17 is frictionally engaged within the well or receptacle only at a single and continuous line of contact of relatively small area and provided by the bead 15. This permits of the easy removal of the screen or shield 16 from the well or receptacle, without danger of the sticking together of the engaged parts, for cleaning or other purposes while providing means for rigidly and firmly holding the screen or shield in normal and operative position. In some cases, instead of providing the base 10 with a bead 12, as described, I prefer to provide the base with a socket 20 as illustrated in the modification shown in Fig. 4. Said socket performs the same function as the bead 12 in that it removably receives and frictionally and firmly holds the lower end of the well or receptacle 13 in proper and operative position.

The construction of ash tray described is particularly desirable in that it contains but three parts each of which is removable from the others so that the device requires but slight care and attention as it is merely necessary to occasionally refill the well or receptacle with extinguishing fluid and to periodically remove the refuse which has accumulated on the base of the ash tray. Also, each of the three parts may be washed or cleaned individually, as is manifest. In use, and as is obvious, when a cigarette is to be discarded after use it is first extinguished by merely inserting its lighted end within the opening 18 and immersing it in the extinguishing fluid. It is then withdrawn and discarded through any of the openings provided intermediate the inclinations 19 of the shield or screen and the corners provided by the intersecting inclined sides of the body of the ash tray all as previously described in detail.

The ash tray itself has a pleasing and ornamental appearance, its objectionable contents in the form of refuse are normally hidden from view by a plate which also provides a support for cigarettes and the like and it may be manufactured in quantities both cheaply and expeditiously.

The invention claimed is:

1. An ash tray having a base and a wall extending upwardly therefrom, an open-ended well containing extinguishing fluid and supported by said base and spaced from said wall and a plate-like device removably supported by said well and adapted to hold a cigarette or the like and provided with an opening therein registering with said well to permit access to the extinguishing fluid therein, said plate-like device extending laterally from said well and hiding said base from

view and forming an opening with said wall for reception of refuse.

2. An ash tray having a base and a wall extending upwardly therefrom, an open-ended well containing extinguishing fluid and supported by said base substantially centrally thereof and spaced from said wall and a plate-like device adapted to hold a cigarette or the like and having holding means frictionally engaging said well and provided with an opening therein registering with said well to permit access to the extinguishing fluid therein, said device extending laterally from said well and terminating adjacent said wall and shielding said base from view and having a portion thereof forming an opening with said wall for reception of discarded articles.

3. An ash tray having a base and a rectangularly-shaped inclined wall extending upwardly therefrom, an extinguishing fluid well frictionally and removably supported by said base substantially centrally thereof and a plate-like shield adapted to support a cigarette or the like having holding means detachably received by said well and provided with an opening therein registering with said well, said shield extending laterally from said well and terminating adjacent said wall and acting as a cover to shield said base and well from view and having portions thereof forming openings with the corners of said wall for reception of discarded articles.

4. An ash tray having a base and a wall extending upwardly therefrom, an extinguishing fluid open-ended well supported by said base, an inwardly extending bead on said well adjacent its upper edge, a cigarette-holding shield covering said base and well and provided with an opening therein registering with said well and a downwardly depending positioning and holding flange on said shield frictionally engaging said head.

5. An ash tray having a base with a socket positioned substantially centrally thereof and a rectangularly shaped inclined wall extending upwardly from said base, an open-ended well containing extinguishing fluid and removably supported by said socket and a plate-like shield for supporting a cigarette or the like and having holding means detachably received by said well and provided with an opening therein registering with said well to permit access to the extinguishing fluid therein, said shield extending laterally from said well and terminating adjacent said wall and acting as a cover to shield said base and well from view and having a portion thereof forming an opening with a corner of said wall for reception of discarded articles.
